UNITED STATES PATENT OFFICE

PETER J. BERTUCCI, OF CLIFFSIDE, NEW JERSEY.

TOY.

1,253,772.

Specification of Letters Patent.

Patented Jan. 15, 1918.

Application filed April 19, 1917. Serial No. 163,096.

To all whom it may concern:

Be it known that I, PETER J. BERTUCCI, a citizen of the United States, and a resident of Cliffside, in the county of Bergen and State of New Jersey, have invented a new and Improved Toy, of which the following is a full, clear, and exact description.

Among the principal objects which the present invention has in view are: to afford amusement and exercise to a person using the toy herein disclosed; to afford means for ascertaining the status of a contest when playing a game using the toy herein disclosed; to increase the skill of a player of a game employing the toy; and to provide a flying device which when properly handled does not bound.

Drawings.

Figure 1 is a perspective view of a racket constructed and arranged in accordance with the present invention;

Fig. 2 is a perspective view of a missile constructed in accordance with the present invention;

Fig. 3 is a face view of a racket as shown in Fig. 1, the game counters thereon being shown as set at zero or the starting position;

Fig. 4 is a vertical section of the missile shown in Fig. 2, the section being taken as on the median line thereof.

Description.

As seen in the drawings, the missile 9 is shaped as a disk and has in the under side a recess 10. Extended from the upper periphery of the missile is a series of feathers 11. The feathers 11 operate to partially suspend the missile 9 when falling through the air and to maintain the missile in an upright position while so falling.

The racket 12 is constructed of thin non-resilient material and has a flat surface adapted to fit the annular edge 13 of the missile 9 to close the entrance to the space or pocket formed of the recess 10. When the racket is disposed to properly receive the missile 9, the air is partially driven from the recess 10 immediately prior to and at the time of the missile striking the surface of the racket. A slight rarefaction of the air in the recess 10 is thereby produced which

operates as a sucker to form a slight but positive attachment between the missile and racket.

On the surface of the racket 12 and preferably adjacent the handle 14 thereof are counters 15 and 16. The counters 15 and 16 are each supplied with a pointer 17. The pointers 17 are pivotally mounted on the racket 12 and concentric with the counters 15 and 16 by means of pins 18. The friction between the surfaces of the racket and pointers 17 is sufficient to hold the pointers stationary when either of the contestants using the racket is playing.

With a racket and missile constructed as disclosed, the game is played as follows: The pointers 17 are initially disposed at the zero point as shown in Fig. 3 of the drawings. One of the contestants is provided with a racket 12. The missile 9 is placed thereon and is tossed in the air by the contestant using the racket to a sufficient height according to the rules or provisions of the game or contest. When the missile falls the contestant catches the same, exercising care or skill to receive the missile in parallel relation to the face of the racket.

The missile is again and again tossed in the air and caught, count being kept of the total number of successful catches. This is continued until by chance or awkwardness the missile is permitted to strike unevenly on the racket in which case it will fall therefrom interrupting the continuation of the "play." The pointer 17 on one of the markers 15 and 16, as the case may be, is moved to show the total number of successful operations by the contestant surrendering the racket.

The second contestant then puts the missile in play and endeavors to excel in number the successful tosses and catches previously accorded to the opposite contestant. When the second contestant fails, his count is accorded on the remaining counter, and the game proceeds by turning the racket over to the first operating contestant who resumes and adds to the total of his count. By a pre-arrangement the game is won by the person first acquiring a certain number of successful tosses and catches.

As distinguished from games of somewhat

similar character, the missile 9 herein used as the flying object has to be brought to a stand and is not battered or tossed in the sense of a ball or shuttlecock. This requirement adds materially to the difficulty and interest of the game.

Claims.

1. A toy comprising a disk-like missile having a recess in the under side thereof; means attached to the opposite side of said missile for retarding the fall of said missile through the air; and a flat-surfaced instrument for catching said missile.
- 15 2. A toy comprising a flat-surfaced racket; a disk-like missile; means for controlling and guiding the fall of said missile through the air; and means for causing said missile to adhere to said racket when dropped thereupon.
- 20 3. A toy comprising a flat-surfaced racket; a disk-like missile; means for controlling and guiding the fall of said missile through the air; and means for causing said missile to adhere to said racket when dropped thereupon, said means embodying a

hollow recess in the striking side of said missile.

4. A toy comprising a flat-surfaced racket; a disk-like missile; means for controlling and guiding the fall of said missile through the air; means for causing said missile to adhere to said racket when dropped thereupon, said means embodying a hollow recess in the striking side of said missile; and visible means mounted on said racket for indicating the status of the play of the person operating the toy.

5. A toy comprising a flat-surfaced racket; a disk-like missile; means for controlling and guiding the fall of said missile through the air; means for causing said missile to adhere to said racket when dropped thereupon, said means embodying a hollow recess in the striking side of said missile; and visible means mounted on said racket for indicating the status of the play of the person operating the toy, said means embodying a plurality of calibrated dials and movable pointers adapted to register with the calibrations on said dials.

PETER J. BERTUCCI.
